DESIGN FOR A SPORTS DRESS

Isaac Rosenberg, St. Louis, Mo.

Application August 24, 1944, Serial No. 115,002

Term of patent 3½ years

(Cl. D3—26)

To all whom it may concern:

Be it known that I, Isaac Rosenberg, a citizen of the United States, residing in the city of St. Louis, State of Missouri, have invented a new, original, and ornamental Design for a Sports Dress, of which the following is a specification, reference being had to the accompanying drawing, forming a part thereof.

In the drawing:

Fig. 1 is a front view and Fig. 2 a rear view of a sports dress showing my new design.

I claim:

The ornamental design for a sports dress, substantially as shown.

ISAAC ROSENBERG.
